Primary Examiner — Stacia Cadmus(74) *Attorney, Agent, or Firm* — John S. Artz; Dickinson Wright PLLC(57) **CLAIM**

The ornamental design for a vehicle wheel, as shown and described.

DESCRIPTION

FIG. 1 is a perspective view of a vehicle wheel, showing my new design;

FIG. 2 is a front view thereof; and,

FIG. 3 is a rear view thereof.

The broken line showing of the lug nut openings, the valve stem opening and the rear portion of the wheel is included for the purpose of illustrating environment and forms no part of the claimed design.

1 Claim, 3 Drawing Sheets**FIG. 1**

FIG. 2

FIG. 3
